(57) CLAIM

The ornamental design for a basketball stand as shown and described.

DESCRIPTION

FIG. 1 is a top, front, right side perspective view of a basketball stand;

FIG. 2 is a front plan view thereof;

FIG. 3 is a right side elevation view thereof;

FIG. 4 is a left side elevation view thereof;

FIG. 5 is a cross-sectional view thereof, taken along section line 5-5 shown in FIG. 2; and,

FIG. 6 is a top, front, right side perspective view of a basketball stand, shown in an environment of use.

The broken lines in the figures depict portions of the basketball stand that form no part of the claimed design.

1 Claim, 6 Drawing Sheets
